UNITED STATES PATENT OFFICE.

HENRY O. WATTS, OF WASHINGTON, DISTRICT OF COLUMBIA.

FLYING-MACHINE.

1,331,299.

Specification of Letters Patent. Patented Feb. 17, 1920.

Application filed July 30, 1918. Serial No. 247,446.

To all whom it may concern:

Be it known that I, HENRY O. WATTS, a citizen of the United States of America, residing at Washington, District of Columbia,

5 have invented new and useful Improvements in Flying-Machines, of which the following is a specification.

The purpose of the invention is to provide a flying machine of the ornithopter 10 type in which there is provided both a novel form of body or fuselage and a novel form of wing, there being also a novel form of steering mechanism. The wings are attached to the fuselage by unique means and 15 are oscillated by a continuously rotating mechanism having connection therewith.

The wings comprise skeleton frames with canvas coverings inclosing the same, the character of the construction being such that 20 an air space exists interior to the wings. By this means the wings are made to simulate those of a bird in shape while the construction is such that a minimum of weight is obtained as well as a maximum of strength.

25 Other and further purposes of the invention are set forth in the following description wherein the same is described in detail.

To the exact construction in which it is 30 shown and described, the invention is not to be restricted. The right is reserved to make such changes or alterations as the actual reduction to practice may suggest provided these changes or alterations are 35 compatible in spirit with the subjoined claims.

The same numerals of reference designate the same parts throughout the several figures of the drawings, wherein:—

40 Figure 1 is a front elevational view of the improved machine.

Fig. 2 is a side elevational view of the same.

Fig. 3 is a top plan view.

45 Fig. 4 is a perspective view of the steering means detached from the machine.

Fig. 5 is a perspective view of a portion of the mechanism by means of which the wings are oscillated.

50 Fig. 6 is a section on the line 6—6 of Fig. 1.

Fig. 7 is a detail sectional view showing a portion of the winged frame and the manner in which the canvas covering of the 55 frame is secured thereto.

Fig. 8 is a detail plan view of the con-

necting ends of the canvas covering for the wings.

Fig. 9 is a plan view of one of the winged frames.

As shown the invention comprises the body or fuselage A, the wings B, and the steering mechanism C.

The fuselage A consists of an open frame 1 the bottom 2 of which is inclined, as 65 shown, when the legs 3 or landing means stand in a horizontal plane. This construction gives the whole fuselage A a tilt with respect to the horizontal. At the bottom 2 of the fuselage there are carried two bearing supports 4 in whose bearings there is journaled the shaft 5. One of these bearing supports 4, the rear one, supports for rotary movement a shaft 6 to the opposite ends of which pedals 7 are connected, the 75 pedals being disposed 180 degrees from each other and being provided for the obvious purpose of turning the shaft 6. This shaft 6 carries a bevel gear 8 meshing with the bevel pinion 9 carried by the shaft 5. Thus 80 the turning of the pedals 7 results in a rotary movement being imparted to the shaft 5 on which there is mounted, in addition to the pinion 9, an eccentric 10 which plays in a rectangular shaped open frame 11, the latter having inturned flanges straddling the eccentric to prevent its, the frame's, lateral displacement. Since the eccentric 10 revolves with the shaft 5, an up and down 85 movement is imparted to this open frame 11 and that during this up and down movement the frame may be held with its greater dimension in a horizontal position, there are provided the guides 12 which are mounted on the bottom 2 and which abut opposite sides of the frame 11.

An operator's seat 14 is mounted on a suitable supporting bracket 15 carried by the frame 1 and this seat is, as shown, positioned conveniently for the operation of the 100 pedals 7.

The top 16 of the frame 1 is closed and at the forward end is of globular conformation, inclining from the top of this globe toward the rear.

105 The wings B each embody a longitudinal tubular member 17 which is hingedly attached, as indicated at 18, one on each side of the machine at the top thereof. The hinged connections 18 are not at the extremities of the tubular member 17 but are so positioned that the inner ends of the said

tubular members may project into the fuselage or body underneath the top 16 and to each of these inwardly projecting ends there is pivotally attached a connecting rod 19, the 5 two connecting rods 19 pivotally connecting with the open frame 11 on the upper edge adjacent the center with one pivotal connection on each side of the center. Since the movement of the pedals 7 serves to raise 10 and lower the frame 11, it is obvious that the connecting rods 19 are similarly raised and lowered with the result that the members 17 are rocked on the hinged connections 18, thus resulting in the oscillation of the 15 wings B of which the tubular members 17 are an essential structural element.

The tubular member is a part of the frame of the wing and attached to it there are a plurality of rods 20, the latter being uniformly spaced along the tubular member from the hinged connections 18 to the outer extremity. Each of these rods 20 is bent 20 to the peculiar conformation shown in Fig. 6, this conformation, of course, varying 25 slightly in shape with each succeeding rod 20 beginning at the hinged connection 18, since the wing B tapers in plan from its point of connection with the fuselage or body A to its outer or free end.

30 The rods 20 being bent to the shape shown and described, their end portions 21 are threaded and passed transversely through the tubular member 17 on the opposite sides of the center of the latter, these threaded 35 ends receiving nuts 22 which seat against washers 23 wedge-shaped in cross-section, as shown, and bearing upon the tubular member 17. It is thus apparent how the rods 20 are attached to the tubular member and 40 how both they and the latter serve to form a frame which when inclosed will provide a wing of the desired shape but with a hollow interior.

The frame comprising the member 17 and 45 rods 20 is inclosed by a canvas or fabric covering 24, the edges of the latter being brought together in the vicinity of the member 17 where the said edges are appropriately connected by means of the lacing 25. 50 That air may be kept from readily entering the interior of the wing thus formed, marginal flaps 26 are stitched or cemented to the covering and after the latter has had its edges laced together, these flaps 26 are cemented together over the row of lacing, thus 55 precluding the ready entrance of air into and the ejection of air from the interior of the wing.

60 It is intended that the canvas covering 24 of the wings shall be continuous over both wings and over the top 16, the necessary shaping of the canvas, of course, being resorted to to have it lie snugly against the wing frames and the top 16. The covering thereby, at the junctions of the wings

and the body supplements the hinged connections 18.

Carried by a universal joint 27 at the end of each wing there is a relatively long thin and narrow plate 28, whose function is to 70 indicate to the operator of the machine the direction in which the wind is blowing.

In addition to the indicator 28, another indicator is provided at the forward end of the machine in the form of a weathercock 29 and 75 just below this latter there is mounted an indicator 30 in the form of a spirit level whose function is to indicate to the operator the lateral inclination of the machine, if it should have any. 80

In addition to the parts previously described there is the steering mechanism C, the latter comprising a plate 31 whose one edge is hingedly connected with the end of a shaft 32 which is carried in bearings 33 85 attached to the top of the frame 1. This shaft 32 may move angularly in the said bearings but it is precluded from longitudinal movement therein. At its forward end which projects beyond the foremost bearing 33, the shaft 32 has pivotally attached to it one end of a depending lever 34 which at a designated point between its handle 35 and its connection with the shaft 32 carries a transverse rod or bar member 36, at 90 the ends of which there are pivotally connected the connecting rods 37. The remaining ends of the connecting rods 37 hingedly or pivotally connect with the plate 31 on the under face thereof. 95

A pair of counter-balancing weights 39 are provided and attached to the plate 31 by appropriate arms 40. Since the shaft 32 may not move longitudinally but may move angularly, it is obvious that a lateral move- 105 ment imparted to the handle 35 of the lever 34 will turn the plate 31 out of the plane in which the machine is flying and, if the handle 35 be moved forwardly or rearwardly at the time of this angular shifting of the shaft 110 32, the plate 31 will be turned to the right or to the left, depending on the direction in which the handle 35 is moved on its pivotal connection and the shaft 32 shifted in its bearing. It is obvious that the plate 31 may 115 be raised or lowered to cause the machine to ascend or descend, or to turn to the left or right, the peculiar construction of the mechanism making it possible to shift the plate 31 up, down, in either direction sidewise, 120 or into a position the resultant of any of these two movements.

While the invention has been illustrated as a foot operated device, it is obvious that a power mechanism may be employed and 125 geared or otherwise connected to the shaft 5, so that the machine may operate as a power machine.

It is to be observed that the distance between the pivotal connections between the 130

connecting rods 37 and the pivotal connections between the shaft 32 and the lever 34 is substantially twice the distance between the pivot of the hinged connection between the plate 31 and the fuselage and the pivotal connection between the said plate and the said connecting rods. Thus in shifting the plate 31 in a vertical plane by means of rocking the lever 34 on its pivotal connection with the shaft 32, substantially twice the angular movement is imparted to the plate 31 that is imparted to the lever 34.

From the foregoing description and the accompanying drawings, it is believed that a clear enough understanding of the invention is to be had and further description is, therefore, omitted.

The invention having been described, what is claimed as new and useful is:

1. In a flying machine, an open frame, wings hingedly attached to the frame at the upper end, a steering mechanism attached to the frame, a shaft, bearing supports carried by the frame for said shaft, an eccentric carried on the shaft, means for rotating the shaft, an open rectangular frame surrounding the eccentric and provided with inturned flanges straddling the eccentric, guides for the said rectangular frame, and connections between the said rectangular frame and the wings whereby the rotation of the shaft will cause the oscillation of the wings.

2. In a flying machine, a fuselage, wings hingedly attached to said fuselage, and means for oscillating said wings, the wings each comprising a skeleton frame and a canvas covering therefor, the frame consisting of a tubular member hingedly attached to the fuselage and a plurality of rod members spaced uniformly along the said tubular member but positioned transversely thereon and connected to the said tubular member, the rod members being of a conformation to give the wing a hollow interior, the canvas covering inclosing the said rod members and

being provided with lacing attaching its marginal edges together and being further provided with marginal flaps whose edges are secured together to inclose the said lacing for the useful purpose hereinbefore specified.

3. In a flying machine, a fuselage, wing frames hingedly attached to said fuselage, each frame embodying a longitudinal tubular member and a plurality of transversely disposed rod members of arched conformation, the said rod members being in the form of open frames, the extremities of the rod members passing through the tubular member and receiving nuts which are threadingly engaged with them to secure them to the tubular member, and a canvas covering inclosing each frame.

4. In a flying machine, a fuselage, wings hingedly attached to the fuselage on opposite sides thereof, an eccentric, means for turning said eccentric, an open rectangular frame surrounding the eccentric, guides for said frame whereby a reciprocating movement of the latter is secured upon rotation of the eccentric, and operative connections between said rectangular frame and the wings for the purpose specified.

5. In a flying machine, a fuselage, wings hingedly attached to the fuselage, a rotating shaft carried in the fuselage, an eccentric carried by said shaft, means for rotating the shaft, an open rectangular frame surrounding the eccentric, guides for said frame whereby a reciprocating movement of the latter is had upon rotation of the eccentric, and a pair of connecting rods, the one end of each of which is pivotally connected to said frame and the remaining end respectively to said wings so that oscillating movement may be imparted to the same by the movement of the said frame.

In testimony whereof I affix my signature.

HENRY O. WATTS.
